LATERALLY EXTENDIBLE SLIDING SHELF

Edward G. Rudman, Nashua, N. H.

Application October 30, 1950, Serial No. 192,924

4 Claims. (Cl. 312—301)

1

This invention relates to a sliding and extendible shelf for furniture; and the object of the invention is to provide a shelf for furniture which may be drawn forwardly from the article of furniture of which it forms a part, and then extended laterally to augment the supporting surface thereof.

A further object of the invention is to provide a shelf, as mentioned, which may be extended laterally in either direction.

A further object of the invention is to provide, in a device as mentioned, means for preventing sagging of the main shelf when extended.

A further object of the invention is to provide means for supporting the laterally extended portion of the shelf when in use.

Other objects will appear hereinafter.

With the above-stated objects in view, the invention consists generally in a drawer adapted to be extended or withdrawn forwardly from the article of furniture of which it forms a part, the upper portion of said drawer forming a shelf, a laterally extendible slide arranged under said shelf, an extendible support for said slide arranged beneath the same, and means actuated by the lateral movement of said slide for moving said support a limited distance under the same.

The invention further consists in various details of construction and combination of parts, as will be described hereinafter and particularly pointed out in the claims.

The invention will be more readily understood by reference to the accompanying drawings forming a part of this specification and in which,

Fig. 1 is a plan view of the device, illustrated as extended forwardly from an article of furniture, and indicating, in dotted lines, the slide and the support for the same extended to the right;

Fig. 2 is a vertical section on the line 2—2 of Fig. 1;

Fig. 3 is a vertical section on the line 3—3 of Fig. 1;

Fig. 4 is a bottom view of the slide; and

Fig. 5 is a plan view of the slide support.

The invention forming the subject matter of this invention is particularly adapted for use in night tables, or the like, and is so illustrated and described herein. However, it is to be understood that the invention is not to be limited to such use but may be used with, or constitute a part of, cabinets of various types.

Referring to the drawings, 10 (Fig. 3) indicates the top of a night table or the like; 11 front vertical frame members, which may constitute the front corner posts; and 12 the top frame front rail.

Slide rails for the device are indicated at 13, and a front rail 14 is in a plane therewith. These elements are conventionally indicated as they

2

may vary according to the type and construction of the article of furniture with which the invention is used.

The drawer 15 in which the slide and slide support are housed, comprises a bottom member 16, a top or main shelf 17, and a front 18 rigidly connecting the same at their forward edges. The bottom 16 is of ample length to extend into the cabinet a sufficient distance to support the device when the drawer is withdrawn to its full extent, and the depth of the shelf 17 is such as to terminate substantially flush with the front of the rail 12 at such time.

Side elements 19 are fixed to the bottom 16 and extend rearwardly from the back edge of the shelf 17 and are adapted to support the rear edge of said shelf. Stop blocks 20 are fixed to the side elements 19 and extend above the plane of the lower edge of the top front rail 12 so as to engage the same when the drawer is drawn forwardly. Preferably, the top ends of the stop blocks are beveled as indicated at 21, and a correspondingly beveled chock 22 is fixed back of the rail 12 to be engaged by said beveled end to prevent any sag of the drawer when withdrawn to the limit. The top shelf 17 of the drawer, and preferably the front 18, are of somewhat greater width than the bottom 16, and stop members 23 are arranged below the level of the under face of the shelf against which the ends of the drawer front 18 abut when the drawer is closed.

Within the drawer above described, is arranged the laterally extendible slide 25 and a support 26 for the same when extended. The slide 25 is substantially the same width as the shelf 17, whereas the support 26 is preferably the same width as the bottom 16 of the drawer; and the projecting ends of the slide are provided in their under faces with finger grip grooves 27. See Fig. 2.

The support 26 comprises generally a rectangular frame consisting of front and back members 28 and 29, respectively, and end members 30; and the slide 25 rests upon the upper edges of said frame members. Arranged forwardly of the member 29 is a longitudinally extending rail 31, and extending between the rail 31 and the front member 28 are a pair of parallel transverse rails 32 which are spaced apart providing a guide-way 33 between them for a purpose hereinafter described.

The rails 31 and 32 are of less height than the frame members 28, 29 and 30, so that the plane of their upper faces is spaced below the under face of the slide 25.

An actuating arm 35 is arranged between the rails 31 and 32 and said slide 25, and is provided at one end with a depending cylindrical hub 36 fitting between the member 29 of the support frame and the rail 31. The hub 36 terminates in

a depending pivot pin 37 seated in a socket 38 in the bottom 16 of the drawer. The opposite end of the arm 35 is provided with a depending lug 39 which extends into the guide-way 33; and also with an upwardly extending lug 40 which projects into a cam groove 41 located on the under face of the slide 25. The lugs 39 and 40 may be formed of a single pin extending through the end portion of the arm 35.

The groove 41 is preferably cut into the under face of the slide and comprises opposite angularly inclined portions 42 diverging rearwardly from a position longitudinally centrally of the slide, and lateral extensions 43 which are in alignment with each other and parallel with the lateral movement of the extension. The lug 39 rests in the groove 41 at the apex 44 thereof when the device is in normal non-extended position, as shown in dotted lines in Fig. 1.

The operation of the device is as follows. When the laterally extendable slide 25 and support 26 are telescoped within the drawer 15, as illustrated in full lines in Figs. 1, 2 and 3, the entire device may be moved into the table or cabinet. When it is desired to use the same, the drawer is pulled forwardly until limited by the stops 20. Then the slide may be extended either to the right or left of the drawer; but in Figs. 1 and 2, it is indicated in dotted lines as extended to the right.

To extend the slide, the finger grip grooves are engaged and the slide pulled in the desired direction. As the slide 25 moves laterally, the lug 40 rides along the left hand angular portion 42 of the groove, thereby swinging the arm 35 to the right. This causes the lug 39, riding in the guide-way 33, to push the support 26 laterally at a slower speed than that of the slide, until the lug 40 reaches the end of the inclined portion of the groove, when further movement of the support is arrested. With further movement of the slide 25, the lug 39 rides along the portion 43 of the groove until the end of said groove portion engages the pin 39, thereby stopping further longitudinal movement of the slide. When the slide is retracted, the pins 40 and 39 reverse its movement in the slot 41 and guide-way 33, respectively, thereby retracting the support 26. It should be noted that the longitudinally extending space 46, between the bar 29 and rail 31 of the support, accommodates the hub 36 of the arm 35 as the support 26 is moved. The slide 25 is prevented from tipping, when extended, by the arm 35 which rests upon the upper faces of the rails 29 and 32, and under the slide 25.

I claim:

1. In an article of furniture, a drawer comprising a bottom and a top, the latter constituting a shelf when the drawer is extended, a laterally extendable slide, and a supporting element therefor slidably mounted between said drawer bottom and top, an arm pivotally connected at one end to said drawer, a transverse guide-way in said supporting element, a lug on the opposite end of said arm and slidable in said guide-way, and cooperating means in said arm and said slide for swinging said arm to cause said supporting element to be moved outward laterally as said slide is extended.

2. In an article of furniture, a drawer comprising parallel top and bottom elements and a front connecting the same, means for limiting the outward movement of said drawer, a slide and

a slide support slidably mounted between the top and bottom elements of said drawer and adapted to be extended in either direction therefrom, an arm pivotally connected at one end to said drawer and positioned between said slide and said slide support, the opposite end of said arm having a downwardly extending lug, a transverse guide-way in said support for said lug, an upwardly extending lug on said arm, and a cam groove in the under face of said slide to receive the last said lug and adapted to swing said arm to cause said supporting element to be moved outward laterally as the slide is extended from said drawer.

10 3. In an article of furniture, a drawer comprising a bottom, a top and a front connecting the same, a slide and slide support mounted between said bottom and top and adapted to be extended laterally therefrom, said support comprising a rectangular frame fitting between said slide and the bottom of said drawer and consisting of front and rear elements and end elements connecting the same, a longitudinal rail spaced from the rear element, and parallel transverse rails extending between said longitudinal bar and said front element, said transverse rails being spaced apart forming a guide-way between them, the upper faces of said longitudinal and transverse rails being arranged below the plane 20 of the upper edges of said frame, an arm having a depending hub arranged between the rear element of the support and said longitudinal rail thereof, and pivotally connected to the bottom of the drawer, a downwardly extending lug on said 25 arm projecting into said guide-way between said transverse rails, an upwardly extending lug on said arm remote from the pivoted end, and a cam on the bottom of said slide to receive the last said lug and adapted to swing said arm to move 30 said support outward laterally as the slide is extended laterally.

4. In an article of furniture, a drawer comprising a bottom, a top parallel thereto and a front connecting the same, a front transverse rail above said drawer, stop members on said drawer adapted to engage behind said transverse rail, means adjacent said rail cooperating with said stop members to level said drawer when 45 fully extended, a laterally extendable slide, and a supporting element slidably mounted between the drawer bottom and top, an arm pivotally connected at one end to said drawer, a transverse guide-way on said supporting element, a lug on the opposite end of said arm and slidable in 50 said guide-way, and cooperating means on said arm, and said slide for swinging said arm to cause said supporting element to be moved outward laterally as said slide is extended.
